HIS ATTORNEY

UNITED STATES PATENT OFFICE.

WILLIAM EIMER, OF NEW YORK, N. Y.

BULLET-PROOF GARMENT.

1,268,223.

Specification of Letters Patent.

Patented June 4, 1918.

Application filed March 30, 1918. Serial No. 225,630.

To all whom it may concern:

Be it known that I, WILLIAM EIMER, a subject of the Emperor of Germany, resident of New York, county of New York, and 5 State of New York, have invented certain new and useful Improvements in Bullet-Proof Garments, of which the following is a specification.

This invention relates to improvements 10 in bullet proof garments and has as its special object the provision of various articles of wearing apparel with means for deflecting bullets from small arms, swords and the like, so as to prevent injury to the body 15 thereby.

A further object is to provide a garment having a series of coverings resembling the scales of a fish, but made of metal so that the same are readily flexed and yet invul- 20 nerable to ordinary small arm projectiles.

A still further object is to provide means whereby the impact of the projectile is substantially cushioned so as to prevent injury by shock or jar transmitted therethrough to 25 the body.

These and other like objects are attained by the novel construction and combination of parts hereinafter described and shown in the accompanying drawing, forming a 30 material part of this disclosure, and in which:—

Figure 1 is a front elevational view, indicating the application of the invention.

Fig. 2 is a rear view of the same.

Fig. 3 is an enlarged transverse vertical sectional view taken on line 3—3 of Fig. 1.

Fig. 4 is a similar enlarged vertical sectional view taken on line 4—4 of Fig. 1.

Fig. 5 is a plan view of one of the plate 40 scales employed, and

Fig. 6 is a fragmentary plan view indicating the relation of the protective elements.

It is to be understood that certain features 45 of the invention may be applied to all kinds and shapes of garments, such as jackets, helmets and the like, the garment itself consisting of a fabric 11, of any strong, woven material, provided upon its exterior with a 50 plurality of over-lapping scale-like elements 12, the separate plates or scales, having secured to their inner sides fastening eyes 13 extending through the fabric 11 and in

which are engaged cords, wires or similar connections 14, thereby holding the scales 55 perfectly flexible but securely to the outer surface of the fabric 11, the ends of the fastenings being secured in any convenient manner.

At the back of the fabric 11 is a relatively 60 thick layer 15 of felt, wool or like material acting in the manner of a pad and adapted to absorb much of the jar or impact which may be transmitted by the contact of a bullet.

Exterior of the pad 15 is another layer 65 composed of woven wire spring 16 or like resilient devices, which make contact with the ordinary clothing worn by the individual and which, in addition to the pad 15, 70 prevents the transmission of shock or jar to the person.

Disposed centrally in front of the structure is a vertical row of overlying steel plates 17, held in similar manner by eyes on 75 their interior surface, and similar overlying plates 17 are disposed over the shoulders, these steel plates being of larger dimensions than the underlying plates which over-lap from the upper row downward, the scales of 80 the horizontal rows overlap those adjacent laterally.

A waist belt 19, adjustable by means of the buckle 20 is furnished with shoulder straps 21, so as to be conveniently carried by the 85 body.

The helmet or cap 25, is comprised of a similar structure which prevents injury being done to the head of the wearer.

I claim:

1. A bullet proof fabric consisting of a layer of overlapping sheet metal elements, a continuous layer of woven wire springs and an intermediate layer of fibrous material between said outer layers.

2. In combination with a fabric, a series of overlapping scales forming an entire layer covering one side of said fabric, means for securing said scales to said fabric, a layer of fibrous material on the opposite side 100 of said fabric, and a layer of wire springs secured to the outer side of said layer of fibrous material whereby the structure is adapted to withstand impact by projectiles.

3. In a bullet proof garment, the combination with a textile fabric, of a plurality of

overlying scale-like metallic plates, eyes set in said plates, said eyes extending through said fabric, securing means engageable in said eyes whereby said plates are held securely to said fabric, a relatively thick layer of fibrous material disposed on the opposite side of said fabric, a plurality of interwoven

wire springs disposed upon the exterior of said fibrous material, and means for securing the garment to a person.

10

In testimony whereof I have affixed my signature.

WILLIAM EIMER.
